TOBACCO RACK

Noah A. Boyette, Rte. 1, Box 200, Hahira, Ga.
Filed Apr. 5, 1962, Ser. No. 185,426
6 Claims. (Cl. 214—5.5)

The present invention relates to the curing of tobacco leaves and more particularly to a rack which may be transported to a field loaded with tobacco and returned to a curing barn where it holds the tobacco leaves while they are exposed to warm air for curing.

Tobacco harvesting is, for the most part, carried out by hand and is slow and laborious. Leaves and stems of tobacco are cut from growing plants by workers who walk along rows. The leaves are tied together in small bundles with string wrapped around the end of the stems, and the bundles of leaves are hung over a stick at spaced intervals. The stick must be carried to a barn where they are hung on supports and the barn is filled with warm air which cures the tobacco.

The method requires considerable handling of individual sticks of tobacco which requires many workers and there may be as many as 8 or 10 men loading a barn. There is also substantial risk of damage to the tobacco.

In addition, there are difficulties with nonuniform curing of the tobacco. The leaves must be loaded in the barn as close to each other as possible so that the maximum number of leaves can be cured at one time. Because of this, the space between the leaves may not be uniform; some of the leaves may be more easily reached by the warm air than others and hence more rapidly cured. In some cases it is necessary to use blowers to force the air among the leaves and to use very hot air at 180° F. or higher temperature to assure that a sufficient amount of air at a curing temperature reaches the less accessible leaves. Unless this is done carefully some of the leaves will be charred by the very hot air. In addition, the high temperature requires large fires and there is a very great danger of setting fire to the barn.

The present invention overcomes these difficulties and provides a rack and means for pinning the tobacco to the rack which can be loaded in the fields and transported to a barn where it holds the tobacco in place for curing. There is no need to tie the stems of the tobacco, to carry individual sticks in the barn or to load the individual sticks in the barn. The tobacco is more evenly spaced and the leaves are sufficiently far from each other that warm air reaches them easily. Because of more uniform spacing the temperature of the curing air can be lower, e.g. 145° F. instead of 180° F. and the curing time may be reduced as much as 24-30 hours. Nevertheless, this uniformity of spacing permits loading 1½ to 2 times as much tobacco in a barn.

These and other advantages are achieved by a rack which comprises a plurality of tiers and braces which hold the tiers in parallel planar spaced relationship. Each of the tiers has a base member and track means at an angle to the base. Tobacco leaves are held in each tier by a stick which has a guide means which moves along the track means toward and away from the base member, a number of spaced parallel pins perpendicular to the base and adapted to be inserted between the stems of the tobacco and a cross-wire running across the pins and holding them together. The cross-wires press the tobacco stems against the base of the tiers. That is, leaves are placed in the rack with the stems lying across the base part of a tier and a stick is pushed down so that the pin passes between the stems and the cross-wire presses the stem against the base. The stick may have a second cross-wire which is spaced above the first cross-wire and

2

this can serve the same function as the base of the tier. Another armful of tobacco leaves is placed with the stems across the cross-wire and a second stick is pressed down against them. The process can be repeated several times until the tier is loaded and then the remaining tiers are also loaded. The rack then is transported to the barn and means are provided for easily moving the racks into position in the barn.

The invention and its object will be fully understood from the following description of a preferred embodiment and by reference to the drawing, in which:

FIG. 1 is a perspective view of the tobacco rack showing a stick being lowered into position;

FIG. 2 is a side view of the rack standing on end showing several layers of tobacco leaves held in place and spaced apart by sticks;

FIG. 3 is a cross-section along lines 3—3 of FIG. 1.

The rack as shown in FIG. 1 has generally U-shaped tiers 1 each having a pair of longitudinally slotted hollow cylindrical vertical track members 2 and 2' which hold the sticks joined by a base member 3 which may be a piece of angle iron. Preferably the base member 3 is set off at one side of the guide members as shown. The tiers are welded or otherwise joined in parallel planar spaced relationship at their tops by two longitudinal angle irons or other suitable braces 4 and 4', and at the bottoms by two similar braces 5 and 5'. At the ends of the frame the upper and lower braces are joined by cross-members 6 and 6' and 7 and 7', respectively. The lower ends of the slotted track members rest on braces 5 and 5' which close the lower ends of the internal hollow cores. There also may be cross spacers not shown to maintain correct distance between braces 4 and 4' and thereby facilitate insertion of sticks.

35 To pin the tobacco in place there are sticks 108 each of which has a plurality of parallel spaced pins 8 of substantially equal length held by cross pieces 9 and 10. The lower cross piece 9 is between the ends of the pin and presses down against the tobacco stems when the ends 40 of the pins, projecting below it, are inserted between the stems. The upper cross piece 10 is shown near the tops of the pins although it may be somewhat lower so long as the space between the cross pieces is sufficient to separate the several layers of tobacco. Of course, additional cross pieces may be added between the two shown for the purpose of added strength.

At the ends of the cross pieces 9 and 10 there are guide members or rods 11 and 11' which join the cross pieces and are of somewhat larger cross section than the pins. 50 They are shorter than the pins and generally of the same length as the distance between the cross pieces. Rods 11 and 11' are of a shape suited to fit in the track members 2 and 2'; when the track members are hollow cylinders, the rods 11 and 11' may be round. The hollow tracks have longitudinal slots 12 and 12' facing toward the center of the rack and these are wider than the diameter of the cross pieces 9 and 10 but not as wide as the diameter of the rods 11 and 11'. This prevents the rods from slipping through the slots so that the sticks can only be inserted and withdrawn from the upper ends of 60 the track.

The rack has hooks 15 and 15' to hold it on end projecting beyond one end and downwardly and rearwardly across the uprights at the corners to which they are welded and toward the lower braces 5 and 5' to which they are 65 also secured. At the opposite ends braces 16, 16', 17 and 17' are fastened and these hold rollers 18, 18', 19 and 19' which are used when the racks are standing on end, especially when they are in the curing barn. There is also provided screening 20 which lines the inside of the rack 70 and prevents the loss of any tobacco when pinned in place by sticks.

To load the rack an armful of tobacco leaves 21 is placed lengthwise in the bottom of the rack with the stems 22 across member 3 and toward the upper end (i.e. the end having hooks 15). The leaves are evenly distributed and then a stick is inserted in the guide members 2 and 2' and pressed down against the leaves. As shown in FIG. 3, the lower ends of pins 8 pass between the stems and cross member 9 presses against them. The next armful of tobacco is laid on the upper cross member 10 of this stick and another stick 108' is inserted in the guides and pressed against it. Then, this loading procedure is repeated and there may be as many as ten sticks in each tier. After inserting the uppermost stick, the pin 13 is inserted in opening 14 to secure the sticks in place. The remaining tiers are loaded in the same manner.

The rack is then transported to the barn which can be equipped for easy loading of the racks. There are a series of tracks, side by side, running perpendicularly to the side of the barn in which there is a door and an overhead hoist is provided which moves on a runway perpendicular to the tracks. The racks are lifted on end by the hoist and suspended by hooks 15. The hoist is moved in its runway until it is above one of the tracks and the rack filled with tobacco is then lowered onto the track and rolled toward the back of the barn. This is repeated until the barn is filled.

Preferably, the rack is about 4 feet deep, 3 feet high and 12 feet long, with the tiers about 2 feet apart. In such a rack there will be 6 tiers, although there may be from 4 to 6 tiers. In each tier there are about 7 to 10 sticks having pins about one inch apart and cross members 2½ to 3½ inches apart. Such dimensions are preferred to permit air to reach the tobacco during curing and are also adaptable to using the rack in a 16 foot barn which would hold 20 racks. In such a barn, the tracks will be about 6 feet above the ground for inside cookers and lower for outside cookers. Of course, these dimensions as well as other details of the construction and mode of operation described may be modified without departing from the scope of my invention, as set forth in the claims.

I claim:

1. A rack for supporting and shaping tobacco leaves during transportation from a field to a curing building and while being cured comprising a plurality of tiers each having track means joined at an angle to a base member, means securing said tiers in generally parallel planar spaced relationship so that when the tiers are in a horizontal position they will lie above one another and will be separated by a distance at least equal to the length

of the tobacco leaves, and sticks for pinning tobacco leaves in place each comprising guide means secured for movement along said track means toward and away from the base member of said tiers, spaced pins generally perpendicular to said base member and secured to said guide means for movement therewith which pass between tobacco stems lying across said base members and a cross member transverse to and secured to said pins intermediate to the ends thereof which presses tobacco against said base member.

5 2. A rack for supporting and shaping tobacco leaves during transportation from a field to a curing building and while being cured comprising a plurality of generally U-shaped tiers each having generally parallel track means joined by a base member, means securing said tiers in generally parallel planar spaced relationship so that when the tiers are in a horizontal position they will lie above one another and will be separated by a distance at least equal to the length of tobacco leaves, and sticks for pinning tobacco leaves in place each comprising guide means secured for movement along said track means toward and away from the base members of said U-shaped tiers, spaced pins generally perpendicular to said base member and secured to said guide means for movement therewith which pass between tobacco stems lying across said base members and a cross member transverse to and secured to said pins intermediate to the ends thereof which presses tobacco against said base.

15 3. A rack for supporting and shaping tobacco leaves as set forth in claim 2 including screening covering at least part of the space between said tiers to prevent the loss of any tobacco leaves not held in place by sticks.

20 4. A rack for supporting and shaping tobacco leaves as set forth in claim 2 in which said tiers are sufficiently deep to hold a plurality of sticks in each tier, each of said sticks having a second cross member transverse to and secured to said pins above the first cross member which serves as a base against which tobacco leaves are pressed.

25 5. A rack for supporting and shaping leaves as set forth in claim 2 having a hook extending from one end for moving the rack into position in a barn.

30 6. A rack for supporting and shaping tobacco leaves as set forth in claim 2 in which the track means are elongated hollow cylinders having slots facing inwardly for passage of said cross members, said guide means being a rod smaller than the internal opening in the track but larger than the width of the slot in the track so that the guide member may be inserted in the track from above but cannot slip laterally through the slot.
